FIG. 1

FIG. 2

FIG. 3

FIG. 4

FIG. 5

FIG. 1 is a top view of a nursery pot cover showing my new design.

FIG. 2 is a front elevation of FIG. 1.

FIG. 3 is a bottom plan view of FIG. 1.

FIG. 4 is a top plan view of a nursery pot cover similar to FIG. 1 showing a second embodiment thereof.

FIG. 5 is a partial front elevation of FIG. 4.

The characteristic feature of my design resides in the specific configuration of the nursery pot cover having first and second vertically spaced flat annular portions each containing a plurality of circumferentially spaced holes.

I claim:

The ornamental design for a nursery pot cover, substantially as shown and described.
